UNITED STATES PATENT OFFICE

165,394

RELIGIOUS PENDANT

Horace Randall, Pawtucket, R. I., assignor to The
H. M. H. Co., a corporation of South Dakota

Application October 3, 1951, Serial No. 16,817

Term of patent 14 years

(Cl. D45—17)

To all whom it may concern:

Be it known that I, Horace Randall, a citizen of the United States of America, residing at Pawtucket, county of Providence, State of Rhode Island, have invented a new, original and ornamental Design for a Religious Pendant, of which the following is a specification, reference being had to the accompanying drawing, forming a part thereof.

Fig. 1 is a plan view of the face of a religious pendant showing my new design;

Fig. 2 is a rear view thereof; and

Fig. 3 is an edge view.

I claim:

The ornamental design for a religious pendant, substantially as shown.

HORACE RANDALL.
